(57) **CLAIM**

The ornamental design for an oval decorative vehicle lighting reflector with segmented reflective surface, as shown and described.

DESCRIPTION

FIG. 1 is a perspective view of an oval decorative vehicle lighting reflector with segmented reflective surface, showing my new design;

FIG. 2 is a top plan view thereof;

FIG. 3 is a bottom plan view thereof;

FIG. 4 is a side elevational view thereof, the other side being identical;

FIG. 5 is an end elevational view thereof, the other end being identical; and,

FIG. 6 is a perspective view thereof, showing my new design in its position of use, it being understood that the broken line (showing the housing, lens and light bulb of the vehicle lighting) is for illustrative purposes only and forms no part of the claimed design.
